The ornamental design for a ceiling lighting equipment for elevator, as shown and described.

DESCRIPTION

FIG. 1 is a front, top, and right side perspective view of a ceiling lighting equipment for elevator, showing a first embodiment of our new design;

FIG. 2 is a front view thereof;

FIG. 3 is a rear view thereof;

FIG. 4 is a top view thereof;

FIG. 5 is a left side view thereof;

FIG. 6 is an enlarged end view taken along line 6-6 in FIG. 2, with the internal system omitted thereof;

FIG. 7 is a front, top, and right side perspective view of a ceiling lighting equipment for elevator, showing a second embodiment of our new design;

FIG. 8 is a front view thereof;

FIG. 9 is a rear view thereof;

FIG. 10 is a top view thereof;

FIG. 11 is a left side view thereof;

FIG. 12 is an enlarged end view taken along line 12-12 in FIG. 8, with the internal system omitted thereof;

FIG. 13 is a front, top, and right side perspective view of a ceiling lighting equipment for elevator, showing a third embodiment of our new design;

FIG. 14 is a front view thereof;

FIG. 15 is a rear view thereof;

FIG. 16 is a top view thereof;

FIG. 17 is a left side view thereof; and,

FIG. 18 is an enlarged end view taken along line 18-18 in FIG. 14, with the internal system omitted thereof.

The broken lines in the drawings illustrate portions of the ceiling lighting equipment for elevator which forms no part of the claimed design.
